(21) Appl. No.: **29/351,837**

(57) **CLAIM**

(22) Filed: **Dec. 11, 2009**

The ornamental design for a rear combination lamp for an automobile, as shown and described.

(51) **LOC (9) Cl.** 26-06

DESCRIPTION

(52) **U.S. Cl.** **D26/28**

FIG. 1 is a front perspective view of a rear combination lamp for an automobile showing our new design;

(58) **Field of Classification Search** D26/28-36;

FIG. 2 is a front view thereof;

362/459-468, 475-478, 485-487

FIG. 3 is a left-side view thereof;

See application file for complete search history.

FIG. 4 is a right-side view thereof;

(56) **References Cited**

FIG. 5 is a top view thereof; and,

U.S. PATENT DOCUMENTS

FIG. 6 is a bottom view thereof.
